FLOWER POT

Elmer B. Brock, 5909 1st Ave. N., Apt. 8,
Birmingham, Ala.

Filed Mar. 30, 1962, Ser. No. 69,503

Term of patent 14 years

(Cl. D35—3)

FIG. 1 is a side elevational view of a flower pot showing my new design;

FIG. 2 is a top plan view thereof; and,

FIG. 3 is a front elevational view thereof; and

FIG. 4 is a fragmentary cross-sectional view thereof taken generally along the line 4—4 of FIG. 3.

Portions of the flower pot are shaded to indicate a contrast of color.

I claim:

The ornamental design for a flower pot, as shown and described.
